APPARATUS FOR TREATING METAL SHEETS

Application filed July 9, 1929, Serial No. 376,940, and in Great Britain July 31, 1928.

This invention relates to an improved method of and apparatus for continuously annealing and cooling metal sheets.

According to the invention the sheets are transported through the furnace and cooling chamber with their planes arranged vertically, whereby a furnace having a cross section of minimum area and efficient shape may be employed, and thus permit a high velocity of gas through the furnace, with an effective transmission of heat to the sheets, so that the latter may be run through the furnace and cooling chamber at an economical speed and be heated and cooled evenly throughout without distortion; the furnace being so sealed that a high furnace pressure may be maintained.

The conveyor by which the transport of the sheets through the furnace and cooling chamber is effected is so arranged that the sheets are supported by their top edges, and so that the main portion of the part of the conveyor carrying the sheets within the furnace is protected from the direct action of the gases, the return portion being exposed to the air for cooling or enclosed in an insulated duct to conserve its heat with inspection covers in same in such manner that it is accessible for repair without dismantling, and may easily be inspected while running, the roofs of the furnace, cooling chamber and conveyor being detachable so that they may readily be removed for repair. The cooling medium in the cooling chamber is preferably the producer gas or other fuel gas for the furnace, the cooling chamber being so constructed that air is excluded therefrom so as to prevent combustion of the fuel gas in the said chamber, said gas in this way being pre-heated; the arrangement also permitting the products of combustion, on leaving the annealing furnace, to be passed through a recuperator in which they are adapted to heat the combustion air for the furnace, and thus reduce the fuel consumption. Each sheet is supported from a conveyor by its top edge, any suitable form of gripping devices on the conveyor may therefore be employed to hold the said top edge; but if the sheets require to emerge from the process without any mark-

ing, such as would result from the gripping of the upper edge, or where such gripping, due to contact with parts cooler than the sheet, would prevent the top edge from being raised to the desired temperature, the size of the sheets fed to the furnace is so arranged that at any stage in the process after the sheet has been through the furnace, a thin strip is cut off that edge of the sheet which was uppermost as it passed through the furnace, thus bringing the sheet to the standard size required.

We find with exceptionally thin sheets of a comparatively large size that, in addition to bending the top edge over at an acute angle as described, a reverse bend should be given so that the configuration of the transverse section of the edge portion has a double fold. The sheets may be passed through the furnace in line in the one vertical plane.

The suspension of the sheets by their top edges enables the sheets to be singly annealed whilst avoiding the difficulties experienced according to present practice in which the sheets are carried on conveyors with their planes horizontal, or with the sheets bent to convex shape; in such cases the sheets, when raised to annealing temperature, become soft, and unless they are supported at numerous points, the sagging due to their weight distorts them.

When suspended by their upper edges, according to the present invention, whether moving in line or broad-side on, the weight of the sheet tends to maintain each part of the sheet in the same vertical plane. The sheets may be fed and removed from the conveyor by automatic means or by hand.

The fuel gases are first fed to the cooling chamber, and as air is excluded from the latter, combustion cannot take place; the sheets are, however, effectively cooled and the said gas, which is preferably washed-producer gas, is thus raised in temperature before it enters the furnace or combustion chamber. The products of combustion of the annealing furnace are led by a flue to a recuperator or heat exchanger in which, for example, the combustion air for the annealing furnace may be pre-heated. Where the products of com-

bustion from furnaces other than the annealing furnace are available for use as cooling gases in the cooling chamber they may be so employed.

5 The conveyor bearings and other bearings or working parts of the furnace or cooling chamber are arranged in accessible positions where they are not subject to the action of the furnace gases, and in which they may be repaired without general dismantling.

15 The conveyor chains, arms and furnace track are preferably made of a material which has a high tensile strength at high temperature so that the furnace conveyor may be stopped and started if desired with the furnace lit up.

We have illustrated our invention in the accompanying drawings, in which:—

20 Fig. 1 is a transverse section of a furnace, cooler and conveyor suitable for sheets fed in line, the plane of section being taken on the line 1, 1 of Fig. 2.

Fig. 2 is a section to a smaller scale.

Fig. 2A is a detail of the sealing rollers.

25 Figs. 3 to 5B show details of construction of the conveyor, carrier bars and clips suitable for use when the sheets are fed in line to the furnace.

30 Fig. 3 being an elevation in transverse section; and

Fig. 3A a side view of a part of Fig. 3.

Fig. 4 is an elevation, in transverse section, of a modification, and Fig. 4A is a perspective view of the carrier shown in Fig. 4.

35 Fig. 5 a front elevation of a further form of the clip.

Fig. 5A a part section on a transverse plane passing medially through Fig. 5; and

40 Fig. 5B is a fragmentary detail view of a cross section of the carrier bar D and shoe d3.

Fig. 6 is a view similar to Fig. 1 showing the arrangement when the sheets are fed with their planes at right angles to the direction of motion.

45 Fig. 7 is a corresponding longitudinal section to a smaller scale.

Figs. 8, 8A and 8B show details of construction of a conveyor and carrier bars suitable for sheets supported with their planes 50 at right angles to the direction of motion.

Figs. 9, 9A and 9B show details of a modification of the last mentioned construction, and Figs. 10 and 10B show further modifications of said construction. In these views 55 Figs. 8, 9 and 10 are elevations.

Figs. 8A and 9B are plan views; and

Figs. 8B, 9B and 10B are end elevations in transverse section.

60 Figs. 11 and 12 are part transverse sections of the furnace showing the mode by which the conveyor chamber is sealed from the furnace.

Figs. 13 to 18 show the different modes in which the upper edge of the sheet may be 65 treated for attachment purposes.

Figs. 13, 15 and 17 being side elevations; Figs. 14, 16 and 18 front elevations, and Fig. 19 a view showing the mode in which a perforated sheet may be utilized without cutting off the edge.

70 Fig. 20 is an elevation of an adjustable opening.

Referring first to Figs. 1 to 5 which illustrate an arrangement when the sheets are fed through the furnace with their planes in a 75 common vertical plane:

A is the furnace which may be of any suitable construction, the top of which is preferably closed by a detachable cover a1 which also forms a cover for the conveyor chamber B, which latter communicates with the top of the furnace by a longitudinal opening b1, the vertical dimensions of which are kept as small as possible, and through which the carrier bars D of the conveyor protrude and to the inner ends d2 of which bars the sheets are attached as hereinafter described.

80 The bars D are attached to links of a conveyor chain d1 which traverses the chamber B from end to end, passing over sprocket wheels K, K', the wheel K being at the front of the furnace and the wheel K' being at the rear end of the furnace or where the furnace is combined with a cooling chamber H as in Fig. 2, the conveyor traverses both the furnace and the cooling chamber, the wheel K' being in rear of the cooling chamber; the plane of rotation of the wheels K, K' is preferably as shown in chain dotted lines k1, k1 Fig. 1, the axis of rotation being k2, k2.

85 The return portion of the chain d1 which extends outside the furnace is shown in Fig. 1, and the oblique arrangement of the sprocket wheels has the advantage of saving space and of relieving the guides on the return journey of the weight of the conveyor bars.

90 In the preferred arrangement there are three fixed guide rails, e1, e2, e3 supported at intervals on a frame E, and the bars D (see Fig. 3) are provided with three shoes d3, d4, and d5, the former two resting on the guides e2, e3 and the latter pressing upwardly on the guide e1, the guides thus serving to hold the bars D horizontal as they pass through the furnace and in the inclined direction shown in Fig. 1 as they return outside the furnace. The shoes d3 and d4 rest on the relatively spaced rails e2 and e3, and are provided with downwardly directed flanges which contact with the inner sides of the rails to hold the conveyor or carrier bars against accidental movement in the direction of their length.

95 The guide rails e1, e2 are staggered so as to facilitate the withdrawal of any of the bars D with minimum interference with the gear.

100 C shows the sheets as they are being con-

veyed through the furnace and cooling chamber.

In order to prevent escape of heated gases from the furnace and in order to prevent the access of air to the cooling chamber H, pairs of sealing rollers F' are fitted at the entrance to the furnace; similar rollers F2 and F3 are fitted respectively between the furnace and the cooling chamber H and at the outlet to the cooling chamber. These rollers are carried in bearings f2, f3 and their peripheries abut with a yielding pressure and they are encased in housings f1 which housings and rollers seal the entrances and exits with the exception, of course, of openings at the top just wide enough to permit the passage of the ends of the carrier bars D. h1 is the top of the cooling chamber, h2 the inlet for the cooling gas (which preferably is the gas employed to heat the furnace, and which may be a washed producer gas) the cooling gas is preheated by heat transmitted to it from the cooled sheets. This gas leaves the cooling chamber by the outlet h3 and passes to the furnace burners.

As stated, the sheets may be attached by their upper edges to the ends of the carrier bars D3 in any convenient manner. We have, however, by way of example, shown three methods of attachment of the sheets in Figs. 3, 4 and 5 respectively, these three methods relating respectively to;—sheets which have their ends turned over as shown in Fig. 13 or Fig. 15; sheets having a plain upper edge adapted to be gripped; and sheets punched with holes c3.

Referring first to Figs. 3 and 3A;—the bars D have a turned down portion d6 ending in an angled portion d2 on which rests the turned over portion c1 of the sheet C, see Figs. 13 and 14; each sheet is supported by several, say four, bars. G are grippers or clips pivoted on the studs g1 attached to the bars D, and having an angular lower portion g2 which presses the portion c1 of the sheet into contact with the angled portion d2; where the sheets have a second bend such as c2, Fig. 15, the portion c2 extends behind the portion g2 so that however thin the sheet C may be, and however hot its edges may be, it is not possible to draw the bent parts through the gripper. Each gripper is provided with a pin g3 which, at that point in the travel of the conveyor at which the sheets have to be attached to the conveyor, or be detached therefrom, engages with a cam bar g4 which turns the gripper about its stud g1 into the position shown in dotted lines Fig. 3A, the cam bar permitting the gripper, when the sheet is in position, to turn about its pivot and grip the sheet as described.

Where the thickness or size of the sheets is such that they may be attached to the carrier bars D by simple gripping pressure, the arrangement is modified as shown in Fig. 4.

The end of the carrier bar D1 has a turned down portion d7 which carries a suitable facing with which the outer face of the upper edge of the sheet engages, the sheet being gripped between this facing and a corresponding facing on the depending portion g6 of a gripper lever G' pivoted at g5 and provided at the other end with a weight g7 which gives the gripping pressure. Said weight has a surface g8 which is adapted to make contact, at the appropriate times, with a cam bar g9 which raises it and so releases the gripping pressure of g6, and permits the sheets to be inserted and removed. In order to protect the corners of the sheets against accidental bending, the ends of certain of the gripper bars may each be provided with a channel-shaped piece d8 between the depending sides of which the top corner of the sheet C is housed.

Where it is permissible to provide the upper edges of the sheets with punched holes c3, as shown in Fig. 18, the arrangement illustrated in Figs. 5 and 5A may be adopted. In this case the carrier bar D2 is provided with a turned down end d9 carrying a pin or hook d10 which pins when the sheets are placed in position are hooked into the holes c3, the sheets being held in position by a gripper G2 pivoted at g10 in brackets g24 formed on the carrier bar D2. The grippers are provided with slots g12 which fit over the pins d10, and each gripper has a lever g11 adapted, when the sheets have to be attached to the carrier bars, or have to be detached therefrom, to engage a cam bar g13 which lifts the gripper G2 clear of the pins d10.

Referring now to Figs. 6 to 10;—in this case the sheets C are adapted to be conveyed through the furnace A' and cooling chamber H' with their planes at right angles to the direction of motion, an arrangement which permits, with a given size of furnace, an increased number of sheets to be in the furnace at a given time and consequently a longer heating and cooling period to be given to the sheets. In this arrangement there is a conveyor chamber B' on each side of the furnace top, each chamber communicating through a longitudinal slot b1 with the furnace. There are two chains d1, one passing through each chamber B', and there is a guide rail e4 in each chamber B'. The pairs of sprocket wheels K2 and K3 are arranged so that their planes of rotation are vertical, the conveyor passing back along the guides e5 carried by girders e6 supported by columns e7; the arrangement being such as to leave clear for lifting the furnace cover, which in this case is made in two halves a2, a3, having a central meeting joint a6. The covers a2 and a3 close in the top of the furnace and the tops of the respective chambers B', and the arrangement of the girders e6 and columns e7 is such that the covers a2, a3 may be removed without in-

terferring with the conveyor; in order to give a straight lift clear of the conveyor, eye bolts a_5 by which the covers are raised are located near the outer sides of the covers, and balance weights a_4 are fitted to the covers so that the centre of gravity of each half is approximately below its eye bolt a_5 . The conveyor bars D_3 extend across from the one chamber B' to the other and are thus supported by the guides e_4 , and driven by chains d_1 at each end.

Figs 8, 9 and 10 show arrangements for attaching the sheets to the carrier bars, the arrangements being respectively applicable to sheets, the upper edges of which are bent, to sheets having plain upper edges, and to sheets perforated on their upper edges.

Referring first to Figs. 8, 8A and 8B;—
 D_3 is the gripper bar supported at each end by shoes d_13 and connected at each end to a conveyor chain d_1 . The bar has depending portions d_12 similar to those of Fig. 3, and each depending portion is provided with a gripper G_3 pivoted at g_14 to the bar D_3 and having a lever portion g_15 the ends of the levers g_15 being adapted to engage with respective cam bars g_16 , and the bars g_16 are so shaped that all the grippers are moved into the position shown in dotted lines on the left hand side of Fig. 8 when sheets have to be inserted or be removed. The sheets may be bent as shown in Fig. 13 or Fig. 15 as may be most convenient.

In the arrangement shown in Fig. 9 and 9A each gripper bar D_4 has depending engaging portions d_14 provided with a facing to take the front face of the top edge of the sheet, and a series of grippers G_4 are provided pivoted at g_17 to brackets g_18 carried from the bar D_4 , and from the shoes d_13 . Each gripper bar has a lever portion g_19 having a turned over weighted end g_20 adapted to engage with cam bars such as g_25 (see Fig. 9B) which release the grippers at points in the travel of the conveyor at which the sheets have to be inserted or removed. In this arrangement the top edges of the sheets are plain.

Fig. 10 shows the arrangement when the top edges of the sheets are perforated with holes c_3 . In this case the carrier bar D_5 is provided with a series of pins or hooks d_16 to take the holes c_3 in the sheets, and the latter are held in position by the gripper G_5 pivoted at g_21 in brackets d_17 carried from the bar D_5 . The gripper bars are slotted as shown at g_26 to clear the pins d_16 , and the gripper has a lever extension g_22 adapted to engage with the cam bar g_23 at points in the conveyor travel at which the sheets have to be inserted or removed.

In the broadside arrangements of the sheets it is of course not possible to employ the sealing rollers F described in connection with Figs. 1 and 2; the openings at the inlet

end of the furnace, the opening between the furnace and the cooling chamber C' and the outlet opening of the cooling chamber are, however, adjusted to suit the size of sheets to be treated, the opening P being adjusted as shown in Fig. 20; interchangeable sliding plates or baffles p_1 , of various widths, are slidably attached to the fixed end plates; and horizontally adjustable side baffles p_3 are fitted which are adjusted to suit the width of the sheet.

Where the sheets are suspended as shown in Fig. 2 overhung carrier bars are preferred, and where the sheets are suspended as shown in Fig. 7, carrier bars supported at both ends are preferred, but either arrangement of carrier bar may be used for either mode of supported sheet, or the conveyor may run above the roof and the carrier bars hung down through a slot in the roof.

Where it is desired to prevent access of hot gases to the conveyor chambers B through the longitudinal slot b_1 , sealing arrangements as shown in Figs. 11 and 12 may be adopted. In Fig. 11 each carrier bar is provided with a V shaped part q_1 , this part q_1 dips into a sealing liquid Q in the continuous V shaped trough q_2 into which liquid dips a fixed longitudinal sealing member q_3 .

In Fig. 12 the part q_1 depends into a trough q_4 a longitudinal depending piece q_3 being fitted as before. In this case an air seal is relied upon.

Where the top edges of the sheets are bent over as in Fig. 13 or Fig. 15, or punched as in Fig. 18 these edges may, as stated, be sheared off by the tinplate maker, or the bent portions may be straightened and the straightened and punched sheets delivered to the user, who, in the act of stamping the parts of metal boxes or the like to be manufactured discards the portions which are unsuitable;—for instance the punching of the box lid c_4 or the like may be accomplished as shown in Fig. 20 so as to reject the portions of the sheets punched with the holes c_3 .

Having now fully described our invention, we declare that what we claim and desire to secure by Letters Patent, is:—

1. In apparatus for annealing metal sheets, in combination;—a furnace; a conveyor traversing the furnace and having carrier bars the ends of which extend downwardly into the furnace; sheet supporting means, carried by the ends of the carrier bars and extending from the said ends beyond the upper edges of vertical sheets to be conveyed and adapted to hold the sheets against downward vertical movement; grippers carried by the said bars adapted to engage the upper portions of the sheets and to retain them in position on the said supporting means.

2. In apparatus for annealing metal sheets, in combination;—a furnace; a conveyor traversing the furnace longitudinally

and having carrier bars the ends of which extend downwardly into the furnace; sheet supporting means carried by the ends of the said carrier bars and adapted to engage with the under sides of the turned-over upper edges of the sheets to be conveyed, and grippers carried by the said bars adapted to engage the upper sides of the said turned-over edges and to retain them in position on the 10 said supporting means.

3. Apparatus for annealing metal sheets, in combination, an elongated furnace, a longitudinally disposed conveyor compartment separate from the furnace, but communicating with the upper part of the furnace through a narrow longitudinal opening, a conveyor traversing the said compartment and having carrier bars extending through said opening into the furnace, supporting means extending upwardly from the ends of the carrier bars within the furnace, and adapted to be engaged by the undersides of turned over top edges of the sheets, and grippers carried by the said bars adapted to engage the upper 20 parts of the said turned over edges to hold the edges of the sheets in position on said supporting means.

4. In apparatus as claimed in claim 3, in which the grippers are pivoted to the carrier bars, members carried by the grippers, and fixed cams having parts inclined to the path of the pivots of the grippers which cams when the grippers reach the point at which the sheets have to be attached to or removed 30 from the conveyor move the said members to open the grippers, substantially as described.

5. In apparatus as claimed in claim 3, in which the conveyor is an endless chain the conveying part of which passes through the 40 conveyor compartment and the return part of which passes outside the furnace, sprocket wheels located at opposite ends of the furnace the planes of rotation of which are inclined to the vertical so that the said return portion of the conveyor outside the furnace is at a lower level than the part of the conveyor within the furnace, substantially as described.

6. In apparatus for annealing metal sheets, 50 in combination, an elongated annealing furnace, a compartment disposed parallel with the upper portion of the furnace and communicating with the furnace through a narrow longitudinal opening, a conveyor passing through said compartment, carrier bars on the conveyor passing through the said opening into the furnace, supporting means on the said carrier bars to carry the sheets, channel-shaped portions formed on the parts of 55 the carrier bars in said opening, a longitudinal member depending from the top of said opening into the said channel-shaped portions, and a fixed channel member extending longitudinally along the bottom of said opening under and receiving said channel por-

tions of the carrier bars and adapted with said portions and said longitudinal member to make a fluid-tight seal between the conveyor chamber and the furnace, substantially as described.

7. Apparatus for annealing metal sheets, in combination, a conveyor traversing the furnace and having carrier bars, and means for suspending the sheets from the carrier bars and including pairs of cooperating sheet gripping members, the members of each pair normally occupying sheet gripping relation, one member of each pair being movable away from the other to effect the releasing of the sheets, and one member of each pair being provided with an upwardly directed pin and the other member being provided with an opening for the reception of the pin.

8. Apparatus for annealing metal sheets, in combination, an elongated furnace, a longitudinally disposed compartment separate from the furnace but communicating with the upper part of the furnace through a narrow longitudinal opening, a conveyor traversing said compartment and having carrier bars for the sheets extending into the furnace through said opening, and means for preventing furnace gases flowing through said opening into said compartment while permitting movement of the carrier bars along 90 said opening.

9. Apparatus for annealing metal sheets, in combination, an elongated furnace, guide rails extending longitudinally of the furnace in relatively spaced relation, shoes slidably mounted on the guide rails and provided with downwardly directed flanges contacting with the inner sides of the rails, carrier bars for the sheets secured to the shoes and having certain ends thereof provided with sheet suspending means, a guide rail located above the other ends of the carrier bars to prevent their displacement from said first guide rails, and means by which shoes and carrier bars may be moved along the guide rails.

10. Apparatus for annealing metal sheets, including a furnace, a conveyor traversing the furnace and having horizontally disposed carrier bars provided with downwardly directed terminal portions, members extending upwardly and outwardly from said terminal portions and adapted to be engaged by the undersides of turned over top edges of the sheets, grippers engaging the upper sides of said turned over edges above the upper ends of said members, and means pivoting the grippers to said terminal portions to adapt the grippers to be swung out of engagement with said turned over edges to free the sheets for removal from said members.

11. Apparatus for annealing metal sheets, including a furnace, a conveyor traversing the furnace and having horizontally disposed carrier bars provided with downwardly directed terminal portions having a fixed posi-

tion with relation thereto, members depending from the carrier bars and pivoted thereto for movement toward and away from said terminal portions, said terminal portions and members constituting sheet gripping means, levers located above the carrier bars and fixed to said members, and providing means by which said members may be moved toward or away from said terminal portions, and 10 weights carried by said levers and normally acting to move them in a direction to urge said members toward said terminal portions.

In testimony whereof, we affix our signatures.
